UNITED STATES PATENT OFFICE.

CHARLES E. JONES, OF CHICAGO, ILLINOIS, ASSIGNOR TO METAL ARTS & CRAFTS CO.,
OF CHICAGO, ILLINOIS, A CORPORATION OF ILLINOIS.

DESIGN FOR AN ARM FOR ELECTRIC BRACKETS AND CHANDELIER.

49,310.

Specification for Design.

Patented July 4, 1916.

Application filed May 26, 1916. Serial No. 100,165. Term of patent 3½ years.

To all whom it may concern:

Be it known that I, CHARLES E. JONES, a citizen of the United States, residing at Chicago, in the county of Cook and State of Illinois, have invented a new, original, and ornamental Design for an Arm for Electric Brackets and Chandeliers, of which the following is a specification, reference being had to the accompanying drawing, forming part thereof.

Figure 1 is a front view of an arm for electric brackets and chandeliers, showing my new design. Fig. 2 is a side view of the same.

I claim:

The ornamental design for an arm for electric brackets and chandeliers, as shown.

CHARLES E. JONES.
